(57) **CLAIM**

The ornamental design for a wheel fixing device, as shown and described.

DESCRIPTION

FIG. 1 is a perspective view of a wheel fixing device, showing my new design;

FIG. 2 is a plan view thereof; and,

FIG. 3 is a front elevational view thereof, the rear elevational view being a mirror image thereof.

A vehicle wheel on which the invented device is mounted is shown in dashed lines, which forms no part of the invented design.
